United States Patent Office.

JULIEN FRANÇOIS BELLEVILLE, OF PARIS, FRANCE.

Letters Patent No. 101,973, dated April 19, 1870; patented in England June 15, 1866.

STEAM-GENERATOR.

The Schedule referred to in these Letters Patent and making part of the same.

To whom it may concern:

Be it known that I, JULIEN FRANÇOIS BELLEVILLE, of Paris, in the Empire of France, have invented certain new and useful Improvements in Boilers or Steam-Generators; and I hereby declare the following to be a full, clear, and exact description of the same, reference being had to the accompanying drawings.

The present improvements are based in principle upon the method of producing instantaneous vaporization in a tubular boiler, by causing the water to pass through tubes plunged into the flame, instead of following the ordinary practice of causing the flame to pass through tubes plunged into the water.

The instantaneous vaporization and non-explosibility are the two essential features which characterize my improved steam-generator.

They are obtained by the combination of water-tubes, placed in communication with the feed-pump by the automatic play of a valve, which itself facilitates the equilibrium of the water introduced and the pressure of steam, and thus establishes in the tubes an ascertained and determinate level.

Steam is generated in proportion to its consumption, and without possibility of its accumulating and causing any danger.

The generator is principally composed of a series of horizontal and vertical tubes, communicating and being in equilibrium with each other, having their lower part plunged in the flame, in order to furnish a heating surface, protected against burning by means of the water with which they are filled to the level regulated by the valve, and receiving the generated steam in their upper part, which communicates with the reservoir for the motive power.

My invention is applicable to engines of all kinds, whether stationary, traction, locomotive, or marine.

The boilers in all such engines will be the same in principle, and will only vary in construction to the extent required to fully adapt them to the locality in which they are used.

The nature of the invention, and the manner in which the same is or may be carried into effect, will, therefore, be readily understood by reference to the accompanying drawings, in which—

Figures 1, 2, and 3 show the whole and the various parts of an apparatus of fifty nominal horse-power for a stationary engine.

Fig. 1 is a sectional elevation of the front of the apparatus.

Fig. 2 is a sectional side elevation.

Fig. 3 is a plan.

Figure 4 represents a modification hereinafter referred to.

A are the generating-tubes communicating with

each other, composed of horizontal tubes superposed quinconcically, connected with each other by boxes and elbow-pipes, and communicating at their lower and upper extremities with tubes which I call collectors.

B is the lower collector, consisting of a tube of square, rectangular, or oblong form, from which the generating-tubes take their feed.

C is the upper collector, in which the product of vaporization in the tubes is received.

D is a tube for dividing or equalizing the supply of steam. This tube is fitted in the interior of the upper collector, where it should be connected steam-tight with the socket of the steam-outlet pipe, so that the steam, in order to escape outside, is caused to become divided, by passing through small holes formed along the upper side of the tube.

The object of these holes, the size of which increases in proportion as they are more distant from the outlet, is to take the steam as equally as possible from the entire length of the collector, in order to regulate the working, and thereby avoid rising and drawing in of the water, instability of the level, and difficulty of maintaining it at a convenient height, defects which, in the absence of this dividing tube, would result from the suction produced at the orifice of the generating-tubes nearest the steam-supply pipe, by intermissions in the expenditure of steam.

E is a superheater or drier, composed of two circulations of tubes, interlacing and crossing each other, and communicating at one extremity with the upper collector C, and at the other with a purifier or chest, F.

This purifier F is fitted with a safety-valve, steam-pipe b, and a dip-pipe, a, for carrying off condensed water, and has an aperture, closed by a door, through which it may be cleaned.

The steam, after leaving the collector, is discharged into this purifying-chamber, where it deposits any grit or impurity it may contain before it passes to the steam-pipe b.

The arrangement of pipes shown in the drawing is sufficient to effect this result, but if desired, a diaphragm-plate may be placed in the purifier, under which the steam must pass before being discharged.

G¹ are junction-boxes of malleable cast-iron, with screwed sockets for joining the horizontal generating-tubes.

H H are mud-hole doors, easy of removal, to allow the interior of the generating-tubes to be cleansed.

I I are brackets for supporting the generating-tubes.

J is a cylinder, fitted with a gauge-glass of the usual construction, with an emptying-cock for indicating the water-level, and with sockets to receive the feed and overflow-pipes.

K is a pipe for returning water from the upper collector to the cylinder J.

L is a pipe communicating between the cylinder J and the lower collector.

M is a graduated cock for regulating the feed.

N is the back-pressure valve.

O is a feed-pipe, putting the cock M in communication with the feed-pump and with the regulating feed-valve, the object of which valve is to allow all the water supplied in excess by the feed-pump to return to the supply-vessel.

P is a pipe which leads the feed-water from the cock M into the upper part of the cylinder J, passing through the valve N.

Q Q are baffle-plates, for turning back the flame and obturators, all for the purpose of dividing the heat and causing it to distribute itself as much as possible over all the surface requiring it, and to oppose the production of too direct currents to the chimney.

R R are soot-doors, to allow the interior of the apparatus and the outside of the generating-tube to be cleansed.

S is the fire-plate.

T is the ash-pit, furnished with a door for regulating the combustion.

U is a damper or register, in communication with the chimney, and serving to regulate the activity of the combustion by means of a chain, counterweight, and index-plate.

V V are jackets or casings of sheet and T-iron.

X is an ordinary brick wall, and

Y, a lining of fire-bricks.

Z is a manometer, in communication with the pipe K or the cylinder J.

The proportions, size, and number of the various parts before enumerated may vary according to the purpose for which the apparatus is intended and its power.

The manner in which the apparatus is set up and arranged will readily be understood.

The tubes of which the boiler or generator proper is composed are arranged longitudinally above the fire-place. The lower collector is supported on the front wall, and on ribs formed for the purpose above the arches of the doors.

In these ribs notches or grooves are formed, which determine the exact position of the collector and form its bed.

The back of the generator rests on a bridge of brick-work at the back of the fire-place, on which bears a cast-iron plate, for forming a regular and solid support, on which the tubes are free to expand.

Each part of the generator is composed of tubes bent into a horseshoe or fork-shape, and they are connected together by screws, sockets, and boxes, which, as well as the lower collector, (and the upper collector if desired,) are furnished with mud-hole doors, on the removal of which the interior of the tubes may be cleansed.

The boxes and the collectors are maintained at the desired distances apart vertically and horizontally by rectangular brackets or supports, which are open-worked, to allow of the passage of brushes, for cleansing the tubes which they cover.

The separation of the bends of the tubes at the back is maintained by disks placed between the bends of each two adjoining horse-shoe tubes, and these disks are mounted on horizontal tubes, with a bolt passing through each concentrically.

These tubes act as distance-pieces between the bends of the generating-tubes, and by tightening the nuts of these concentric bolts, flat iron bracing-pieces, fitted vertically at each side of the generating-tubes, are pressed against the ends of the stay-tubes, which limit the tightening, while allowing the bends sufficient play for the generating-tubes to expand or dilate at the back as at the front.

The flat braces are bent upon the tubes of the two outer horseshoe-tubes, to keep the whole number of tubes firmly together.

The generator thus united and stayed possesses perfect solidity and homogeneity, and works as if it were in a single piece.

A fixed sheet-iron baffle-plate is arranged transversely in the center of the generator, to avoid the action of direct currents, and to cause the products of combustion to be distributed as equally as possible over all parts of the generator.

On each side of the generator, between the brick-work and the tubes, that is to say, in the part where the quincunx is not continued, an obturator is fitted longitudinally, to stop the too direct passage of the flame.

A plate or partition for turning back the flame covers the hinder part of the generator for about two-thirds of its length; that is to say, that it leaves free at the front a sufficient passage for the products of combustion. It is pierced with holes.

This partition is indispensable on the one hand, because, the air being always admitted into the ash-pit, from the front to the back, at a certain speed, the result is that the combustion is always more active at the back part of the fire-bars, and that in consequence of the direction of the current of air, the flame has a great tendency to proceed toward the back of the generator. It is therefore necessary, in order to utilize the whole heat, to cause the hot gases to return to the front.

On the other hand, in the arrangement shown in the drawing, the chimney-damper being placed at the back of the generator, this partition for turning back the flame is necessary to prevent the formation of a direct current to the chimney.

The superheater placed above this partition rests at each side upon the brick-work. It communicates at its front end with the upper collector, and at its back end with the purifier.

This superheater is applicable to the three kinds of boilers before mentioned.

The superheater, as shown in the drawings, is composed of two coils or circulations of tubes, interlacing or crossing each other. It is superior to superheaters formed of only one coil or circulation of tubes, for the reasons that the total internal section of its tubes is greater, it possesses more rigidity, the spaces between the tubes are nearly equal in all directions, and form narrow flues, preserving a large section for the passage of the hot gases; the brushing of the tubes is performed in a more perfect manner, as the brush, when passed into one of the flues, is naturally and forcibly applied against the top of one tube and the bottom of another; the hot gases are more divided, and the extraction of their heat is more complete.

At its end the superheater is also furnished with a sheet-iron obturator, fitted vertically in front of the opening of the chimney-damper. This obturator causes the gases to be distributed over all the extent of the superheater, by preventing them from passing direct to the chimney.

The two coils of tubes in the superheater are stayed, so that all the tubes are maintained apart.

a, in figs. 1, 2, and 3, is a dip-pipe for clearing out the superheater.

b is the steam-pipe leading to the engine.

d is a movable shield or air-jacket, to prevent radiation from the front of the boiler.

e is an intermediate covering, for parting off and closing the space between two adjoining boilers.

In cases where the chimney is placed on the top of the generator, as represented by the sectional side elevation in fig. 4, which illustrates an arrangement for a fifty-horse power stationary boiler, specially in-

tended to utilize waste flame and heat, the partition or plate for turning back the flame is dispensed with; or rather, it is placed on the top of the superheater as an obturating-plate. It covers the superheater so as to leave only sufficient opening for the easy passage of the gases.

This opening for the gases is apportioned between the front and the back of the generator, in the inverse ratio of the facility with which the products of combustion have a tendency to pass at one part or the other.

When the chimney communicates with the top of the generator, the purifier is placed at the side, as in fig. 4.

a, fig. 4, is the chimney.

b is a door for getting at and clearing out the ashes.

d, a perforated plate for the admission of air.

e, the channel or passage leading to the same.

f, the waste-flue from the oven-furnace.

g, a bracket for supporting the purifier, and

h h are soot-doors placed in the side-walls.

The working of the boilers is as follows:

During the working the regulating feed-valve, which is in constant communication with the feed-pipe, being charged to the desired pressure, the water furnished by the feed-pump, or by any other means, enters the upper part of the cylinder J by the graduated cock M and by the valve N.

The cylinder J being in communication with the upper and lower collectors B and C, has thus perfect equilibrium of pressure with the interior of the generator.

From the cylinder J the feed-water passes into the lower collector, and rises simultaneously into the generating-tubes until its level is the same in the tube as in the cylinder J, and, consequently, in the gauge-glass on the cylinder.

The lowest tubes, that is to say, those nearest the fire, are traversed by the current of water at the least elevated temperature. They are thus not liable to injury from the fire.

It is in the second and third rows of tubes that the boiling is the most active, and that the steam bubbles, as they become disengaged, draw with them a relatively large quantity of water in the vesicular state.

These drops, to which the steam acts as a vehicle, are rapidly vaporized by contact with the tubes of the upper rows. Then the whole of the steam thus formed is dried before reaching the purifier, into which it issues by passing through the orifices of the tubes D

for dividing the steam-supply, which tube equalizes the work between the different units.

The drier E is applicable to all kinds of apparatus, such as described. In those which are provided with it, the steam, normally very saturated, reaches the upper collector, from which the water drawn in excess returns to the cylinder J by the return-pipe K. The steam is then dried by circulating through the superheater E.

In apparatus not provided with the superheater the generators are generally composed of a greater number of tubes of such height that the drying of the steam is effected therein. If under these circumstances any water was drawn into the upper collector, it would return by the pipe K into the cylinder J, as before explained.

The pipes for conveying the steam to the engines are fitted on the purifier F.

Having now described my invention, and the manner in which the same is or may be carried into effect, What I claim, and desire to secure by Letters Patent, is—

1. The employment, with steam-generating tubes arranged substantially as described, of a cylinder or other suitable vessel, J, connected and communicating with the highest and lowest series of said tubes, and with the water-feed, substantially in the manner and for the purposes set forth.

2. The combination of the generating-tubes, upper and lower collectors, and external cylinder, communicating with said collectors and with the water-feed, under the arrangement and for operation as specified.

3. The employment within the upper collector of a tube, connected with the steam-outlet, and perforated to divide the supply of steam, substantially as shown and described.

4. The combination with the generating-tubes and upper and lower collectors, communicating with the equalizing and feed-cylinder, as specified, of the purifying-apparatus, connected either directly with the generating-tubes or with the superheater or drier, interposed between it and the tubes, as and for the purposes set forth.

In testimony whereof I have signed my name to this specification before two subscribing witnesses.

J. F. BELLEVILLE.
